UNITED STATES PATENT OFFICE.

WILLIAM H. BURGESS, OF RICH SQUARE, NORTH CAROLINA.

CRADLE.

SPECIFICATION forming part of Letters Patent No. 281,966, dated July 24, 1883.

Application filed January 11, 1883. (No model.)

To all whom it may concern:

Be it known that I, WILLIAM H. BURGESS, of Rich Square, in the county of Northampton, and in the State of North Carolina, have 5 invented certain new and useful Improvements in Combined Table, Stand, Desk, and Cradle; and I do hereby declare that the following is a full, clear, and exact description thereof, reference being had to the accompanying drawing, and to the letters of reference marked thereon, making a part of this specification.

This invention relates to certain new and useful improvements in the construction of 15 cradle-stands; and it consists in the employment of metallic wire, several strands of which are twisted together in such manner as to form a light, durable, and inexpensive frame-work, as will be more fully hereinafter specified.

20 In the accompanying drawing, forming a part of this specification, in which like letters of reference indicate corresponding parts, a perspective view of my improved cradle-stand is shown.

25 The letter A indicates the body or main portion of the stand, said body being composed in the present instance of three strands of wire twisted or bound together. These wires radiate at each end of the body A, and form, 30 respectively, upright standards B and supporting-legs C. The former terminate each in an eye, b, for a purpose which shall presently appear, and the latter are each bent downwardly, so as to rest firmly on the floor.

35 The letter D designates braces, the same consisting of wire, preferably smaller in di-

ameter than that constituting the frame proper, the said braces being wrapped or twined around the legs and the standards for a portion of the length of each. These serve to give rigidity to the stand and to prevent vibration or bending of the standards by the swinging of the cradle. 40

The letter E refers to the hangers by which the cradle is supported, the same consisting of 45 short sections of wire provided each with a bend near the middle, upon which they oscillate in the eyes b of the standards B. The ends of the said hangers are preferably formed into hooks which serve to engage with the devices 50 employed in connecting the cradle therewith.

Having thus fully described my invention, what I claim as new, and desire to secure by Letters Patent, is—

1. A cradle-stand consisting of a plurality 55 of wire strands twisted or bound together, the ends of which are suitably bent or directed to form the supporting-legs and standards, substantially as described.

2. A cradle-stand constructed of a plurality 60 of wire strands united, and having the ends bent to form the supporting-legs and standards, and provided with braces and cradle-hangers, substantially as specified.

In testimony whereof I affix my signature, in 65 presence of two witnesses, this 1st day of January, 1883.

WILLIAM H. BURGESS.
